United States Patent Office

Des. 229,075
Patented Nov. 6, 1973

229,075

PUPPET

Christopher S. Crowell, Darien, Conn.
(242 Main St., Southport, Conn. 06494)

Filed Aug. 9, 1972, Ser. No. 279,093

Term of patent 14 years

Int. Cl. D21—01

U.S. Cl. D34—2 R

FIG. 1

FIG. 2

FIG. 3

FIG. 1 is a front view of a puppet embodying my new design;

FIG. 2 is a rear view of the puppet of FIG. 1; and

FIG. 3 is a side view of the puppet of FIG. 1.

I claim:

The ornamental design for a puppet, substantially as shown and described.
